UNITED STATES PATENT OFFICE.

WILLIAM W. WALLACE, OF SPRINGFIELD, MASSACHUSETTS.

PIANO-ACTION.

SPECIFICATION forming part of Letters Patent No. 519,166, dated May 1, 1894.

Application filed September 19, 1893. Serial No. 485,830. (No model.)

To all whom it may concern:

Be it known that I, WILLIAM W. WALLACE, a citizen of the United States of America, residing at Springfield, in the county of Hampden and State of Massachusetts, have invented new and useful Improvements in Piano-Actions, of which the following is a specification.

This invention relates to improvements in piano actions, more particularly to actions for upright pianos.

The object of the invention is to simplify the action and to generally improve and render more efficient the principal operating parts, as will be hereinafter rendered manifest.

15 The invention consists in constructions and combinations of parts, all substantially as will hereinafter fully appear and be set forth in the claims.

Reference is to be had to the accompanying drawings, in which these improvements are illustrated.

Figure 1 is a sectional side elevation of the upright action. Fig. 2 is a longitudinal vertical section on an enlarged scale of the 25 "flange," or journal support for the hammers, jacks and similar lever-like parts, which support embodies the improvements to be hereinafter specified, and Fig. 3 is a perspective view of the same, while Fig. 4 is a plan view 30 of the metallic blank from which the improved journal support is in part formed.

In the drawings, A represents, in vertical cross section, the center rail for the action, B the lower rail, C the jack-lever rail, D the hammer-rail, and E the regulator rail. The center rail, A, is stepped at its rear and has pivotally mounted thereon, the hammer, F, as usual. The hammer rail, D, having the layer of felt, is located suitably above and slightly 40 in advance of the center rail for the rest of the hammer thereupon when the hammer is in its normal position. The upright damper lever, a, is intermediately thereof, pivotally mounted upon the rear step of the center rail, 45 this lever carrying the upwardly extended wire stem, or shank, a², with the damper, a³, at its upper end, the spring, a⁴, serving to normally maintain the damper rearwardly 50 swung to its bearing against the string, x. 50 The jack-lever-rail is suitably in advance of and slightly below the center rail and the jack-lever, G, is, intermediately thereof, piv-

otally mounted upon the said rail, this lever being nearly upright with, however, a forward and upward inclination, as seen. The 55 jack, b, is of a usual form, it having its longer member rearwardly extended to engagement with the shoulder of the hammer-butt, while its shorter member b², is upwardly extended at the elbow, its upper end being formed with 60 the downwardly and rearwardly inclined nose, which is bushed with felt, and with which engages the button, d, of the "cut-off," or regulator.

Upon the lower rail, B, which ranges transversely across the series of keys, one of which is indicated at H, is pivotally mounted, at its elbow, the bell-crank or angle-lever, f, the upwardly extended arm of which is extended to within a short distance in advance of the 70 lower extremity of the jack-lever, the link, g, connecting these contiguous members. The key has at its rear the upwardly extended shank or stem, i, with the wooden stud i², at its upper end, the latter having a rounded 75 top which is in bearing against the under surface of the rearward horizontal member of the aforesaid elbow lever, all so that the depression of the key, at its front, causing the elevation at the rear, insures, through the elbow lever and link connection with the jack-lever, the rearward swinging movement of the upper member of the jack-lever, insuring the operation of the hammer, the release of the damper, and the carrying of the back- 85 check into position to intercept the hammer, on its rebound, against returning entirely to its normal position, for the usual facility and rapidity in repeating a note. The back check consists of the rearwardly and upwardly inclined wire or stem j, which has connection 90 with the upper member of the jack-lever, this stem having at its rear end the felt bushed check-block, j². The parts are arranged and adjusted so that as the hammer is thrown 95 against the string, the back-check assumes, while the key is still held depressed, a position of approximately half an inch, or less, to the rear of the forward end of the hammer at the instant the hammer is on the key, the 100 hammer having only the stated distance of rebound.

The purpose and operation of the back-check are well understood to those skilled in

the art to which this invention appertains, and the novelty with respect to this device in the present invention consists in the relative arrangement of the hammer, jack, and 5 jack-lever, with the back-check rearwardly extended from the upper extremity of the jack-lever. The regulating screw, d^2 , is vertically adjustable by screwing down through the regulator-rail, E, the button, d , having its 10 lower portion in the form of an inverted cone, which form, together with the adjustability thereof and its juxtaposition with the nose of the jack, constitutes a cut-off or regulator which is capable of great efficiency and nicety 15 of operation. The damper-lever, a , has, on its depending arm, the forwardly extended member, a^5 , with the smooth, rounded extremity, interposed between which and the jack-lever, at a point on the latter a short 20 distance above its pivotal support, is the horizontal reciprocating push-rod, m , the latter having slide bearings through the horizontally apertured lower portion of the center rail, A. This push-rod has, at each end, the 25 felt covered buttons, l , l^2 , the latter being normally in contact with the said rounded extremity of the damper member, a^5 , while with the forward button contacts the button-provided rear end of the screw-shank, n , 30 which is adjustable forwardly or rearwardly, as desired, through the jack-lever. The center rail is preferably formed with the groove at its lower part, as seen at o , whereby the bearing surface imparted to the push-rod is 35 lessened, and the hole through the said apertured portion of the center rail, through which the push-rod slides, is bushed or lined with felt for the obvious purpose. In this 40 action an improved form of "flange" or journal support and connection is illustrated which is adapted for employment at various parts of the action, as between the jack-lever and the jack-lever-rail,—between the jack-lever and jack,—between the center rail and 45 hammer-butt, or damper-lever, one or both, and between the lower rail and elbow lever. This journal support, or "flange," as this part is sometimes termed in piano actions, is in part formed of a single blank of thin metal 50 of rectangular form, as seen at Fig. 4, with an inclosed rectangular opening, p , therein. This blank has intermediate portions thereof overturned on bending lines which traverse said aperture to form the opposing apertured 55 or loop-like ear pieces, q , see Figs. 2 and 3, the end portion of the blank being superimposed and riveted together forming the base or foot piece to be attached by screws, or otherwise, to the rails. Within the 60 opposing ear pieces formed as described, are set small blocks or sections r , of wood having the transversely aligned holes therein, which are bushed or lined with the felt t , within and next to which bear the pivots, y , for the various devices which are hung within these 65 ear pieces. These "flanges," or journal supports, constructed as described, are less af-

fected by atmospheric changes than those heretofore usually employed, which were constructed of wood. They are also capable of 70 production easily and cheaply.

Having thus described my invention, what I claim, and desire to secure by Letters Patent, is—

1. In an upright piano action, the combination with a jack-operating lever and the damper-lever, both pivotally mounted for swinging movements in corresponding vertical planes, of a rod horizontally mounted for a reciprocating endwise movement adapted to 75 be pushed at one end by the jack-lever, and to push and swing by its other end the damper-lever, substantially as described.

2. In an upright piano action, the combination with a jack-operating lever and the 80 damper-lever, both pivotally mounted for swinging movements in corresponding vertical planes, of a rod horizontally mounted for a reciprocating endwise movement adapted to be pushed at one end by the jack-lever, and to 85 push and swing by its other end the damper-lever, and a spring for retracting the damper and push-rod on the return movement of the jack-lever, substantially as described.

3. In an upright piano action, the combination with the jack-lever and the damper-lever mounted for swinging movements in 90 vertical planes, of the interposed horizontal endwise reciprocating push-rod having one end in contact with the damper-lever and having 95 its other end adjacent and in the plane of swing of the jack-lever and the adjusting screw on the jack-lever having an endwise bearing engagement on said push-rod, substantially as described.

4. In an upright piano action, the combination with the center rail and the hammer pivotally mounted thereon, and the damper also pivotally and intermediately mounted therein having the forwardly extended member 100 on its depending arm, and the jack-lever pivotally and intermediately supported forward of the center rail, and the horizontal push-rod playing through guide-ways therefor in the center rail and having buttons on its ends, 105 one of which has a contact engagement with the said member of the damper and the screw adjustable through the jack-lever and having the button on its rear end having a contact engagement with the adjacent push-rod button, and the damper spring, substantially as 110 described.

5. In an upright piano action, the combination with the lower rail, and the elbow lever pivotally mounted thereon, of the key having 115 at its rear the upwardly extended stud in contact bearing upon the horizontally extended member of the elbow lever, the intermediately pivoted upright jack-lever, and a link connecting its lower end to the upwardly extended arm of the elbow lever, substantially as described.

6. In an upright piano action, the combination with the lower rail, and the elbow lever

5 pivotally mounted thereon, of the key having at its rear the upwardly extended stud in contact bearing upon the horizontally extended member of the elbow lever, the shank or stem of said stud having a vertically adjustable screw engagement in the key, the intermediately pivoted upright jack-lever, and a link connecting its lower end to the upwardly extended arm of the elbow-lever, substantially 10 as described.

15 7. In an upright piano action, the combination with the hammer formed and pivotally mounted as usual, of the upright intermediately pivoted jack-lever having the jack pivoted thereon and provided, near its pivot, with the upwardly extended member, the regulating rail, and the vertical regulating screw having on its lower end the conical button, the apex of which is downward, substantially 20 as described.

25 8. In an upright piano action, the combination with the pivoted hammer, of the jack, and the upright lever on which the jack is pivotally mounted having in its upper extremity the rearwardly extended stem with

the back-check locked at its extremity, substantially as described.

9. In a piano action, a "flange" or journal support for the hammers, jacks, and similar lever-like parts, comprising a metallic body 30 or base, and opposing metallic apertured ear-pieces, sections of wood set in said ear-pieces with aligned journal holes, and bushings of felt, or the like, lining said holes, substantially as described. 35

10. In a piano action, a "flange" or journal support for the hammers, jacks, &c., formed of a single blank of thin metal with an enclosed rectangular opening therein, as shown, the same having intermediate portions overturned on bending lines traversing said aperture to form the opposing apertured or loop-like ear-pieces, and the superimposed end portions riveted together, substantially as described and shown. 40
